UNITED STATES PATENT OFFICE

ANDREW MAIN, OF CLEVELAND, OHIO, ASSIGNOR TO THE FOUR-WAY LOCK COMPANY, OF CLEVELAND, OHIO, A CORPORATION OF OHIO

CYLINDER LOCK

Application filed October 17, 1929. Serial No. 400,270.

This invention relates to cylinder locks, its object being to provide an improved construction in which the duty of throwing the bolt is taken away from the ward portion of the key and is assumed by a separate driving part thereof, which consequently will be of heavy form suitable for operating heavy lock mechanisms, such as jail locks or the like, without injury to the key, and which invention at the same time admits of lock protection by a multiple ward key.

In the drawing, which represents one suitable embodiment of the invention, Fig. 1 is a front elevation of the casing and lock mechanism, with the cover omitted; Fig. 2 is a detail cross section on the line 2—2, Fig. 3; Figs. 3 and 4 are respectively cross sections, on a larger scale, on the lines 3—3 and 4—4, Fig. 1; Fig. 5 is a detail section on the line 5—5, Fig. 4; and Fig. 6 is an elevation of the key.

While the present invention is useful on any kind, size or style of lock, it has been more particularly designed for the control and operation of relatively heavy locks, such as jail locks, where the dead bolt is a relatively heavy piece of metal, and the other operating parts of the lock are also heavy, so that unavoidable frictional resistance to bolt throwing movement is involved and a relatively strong key is essential. The drawing shows for convenience a simple form of jail lock, comprising a casing including a hollow body portion 1 and a suitable cover 2 in which are mounted the slidable dead bolt 3 and the control lever or levers 4, shown as pivoted at 5 and yieldably moved in one direction by suitable springs 6. Said levers are provided with shaped slots or openings 7 cooperating with a lug 8 on the dead bolt, it being necessary to move the levers laterally or transversely to the direction of sliding bolt movement until they reach certain definite positions, as shown in Fig. 1, before the bolt can move, it being also understood that said levers lock the dead bolt in either of its two positions, as is usual.

The lock actuating mechanism includes an operating part, shown as rotatable, the motion of which first sets the levers 4 and then

throws the bolt, later permitting the levers to return to latching position.

The operating part referred to, in the form shown, is a rotatable sleeve 9 provided at one point with an actuating arm 10 which engages both the levers and dead bolt to operate them, as shown in Figs. 1 and 4. Said sleeve forms a part of a cylinder lock unit capable of being assembled on the bench as an entirety and of being inserted into or removed from the lock casing, enabling units to be interchanged for combination purposes or otherwise. Also, as shown, the lock casing is arranged to receive two of such units in reversed position, each unit having the necessary lever and bolt throwing arm, so that an operating key can be inserted into the lock from either side. Of course, the two units engage the levers and bolts at different points, but their manner of actuation thereof is the same. By using two units in staggered relation, the entire lock casing may retain comparatively shallow depth. For simplicity, it will be necessary to describe but one of said units, because, except for differences in the arrangement of the bolt throwing arms, they are alike in all respects.

Each unit comprises the sleeve 9 before referred to and within it a lock cylinder or barrel 11, closed at one end and open at the other and within which rotates the central plug 12. Said plug is, of course, cylindrical in form, but at one end it is provided with a non-circular portion 13, such as a squared portion, fitting a like opening 14 of the sleeve head 15 and serving as a driving connection between the sleeve and plug. The cylinder or barrel 11 is provided with an annular flange 16 notched at several points, such as at 17, to receive lugs or projections 18 which are rigid with the casing, and which, for example, may extend upwardly from a disc or washer 19 attached thereto or integral therewith. The casing cover is usually also provided with a hollow boss 20 provided with an annular seat 21 to receive an annular flange 22 of the sleeve 9, and which also serves to enclose the end head 15 of the sleeve, and which hollow boss is provided with a circular opening 23 through which the key is inserted, said opening being usually provided with a notch or 100

extension 24 at one side through which it is necessary to pass a pin 25, insuring that the key 26 be introduced in the lock in the desired position and in no other.

5 The lock may be provided with any suitable tumbler mechanism between plug and barrel respectively, requiring proper positioning thereof before the plug can be turned. This may either be pin or lever mechanism, but is 10 shown as lever mechanism of the general form described and claimed in a prior patent, No. 1,594,297, granted July 27, 1926 to James A. Muzzio, to which reference may be had for a more complete description thereof if necessary. Briefly described, the key and tumbler mechanism is as follows:

20 The key is what is known as a four-way key, its ward portion 27 being of cruciform cross section, providing four wards, the edges of 25 which are formed on combination principles. The plug is slotted longitudinally and transversely to form intersecting slots 28, Fig. 2, into which the key can be introduced. In said slots are located spring pressed pivoted levers 29 adapted to enter or leave longitudinally 30 extending slots or recesses 30 of the cylinder.

25 The key not only includes the ward portion 27, but inwardly thereof it is also provided with a heavier and stronger lock driving or operating portion 31, which is preferably non-circular, such as square, and is designed to engage with a similarly shaped recess 32 of the sleeve. On this driving portion is located the pin 25 before referred to. The shank and 35 handle of the key may be of any suitable form, and heavier, if desired.

30 When the key is inserted to home position, as shown in Fig. 3, the several wards move the tumblers, such as the levers 29, to release position and in the particular form shown, so that they are entirely free of the slots 30 of the cylinder. In the same position of the key the pin 25 has passed the gateway and lies in an annular recess 33 within the boss 20, and the non-circular driving portion 31 of the key lies within the recess 32 of the sleeve. In this position, therefore, the key has released the plug so that it will turn in the barrel and it has also established driving relation with the sleeve. Consequently, the key may be rotated to thereby turn the sleeve 9 and cause its arm 10 to actuate the lock levers 4 and dead bolt 3 in the usual manner. The key cannot be withdrawn unless the pin 25 is opposite its gateway, so that the key can be introduced into the lock in only one position. Of course, in other positions its wards would not properly actuate the tumblers.

35 With this arrangement, the duty of throwing the dead bolt is entirely taken away from the ward portion of the key and is assumed by the heavier driving portion of the key 31, so that the key is not likely to suffer injury during operation.

What I claim is:

1. Lock mechanism, comprising a casing, and a cylinder lock unit insertable into said casing and provided with relatively rotatable cylinder and plug members, connecting means 70 between said casing and cylinder member for preventing rotation of the latter, and a lock operating member rotatable around the cylinder member and operatively coupled to the plug member.

2. Lock mechanism of the character described in claim 1, said lock operating member being provided with means adapted for direct driving connection to a key.

3. Lock mechanism, comprising a casing, a dead bolt movable therein, control levers therefor, and two cylinder lock units lying side by side in said casing but reversed in position and adapted to separately receive a key introduced from either side of the casing, said units being each provided with operating means for actuating said control levers and dead bolt.

4. Lock mechanism, comprising a casing, a dead bolt movable therein, and a cylinder 90 lock unit removably fitted to said casing, said unit comprising relatively rotatable cylinder and plug members, a bolt operating sleeve surrounding the cylinder member and rotatable with the plug member, and means for preventing relative rotation between the cylinder member and casing.

5. Lock mechanism comprising associated cylinder and plug members, and a lock operating member sleeved upon and rotatable 100 around said cylinder, said plug member and lock operating member both being provided with means adapted for driving engagement with a key.

6. Lock mechanism comprising associated cylinder and plug members, and a lock operating member sleeved upon and rotatable around said cylinder, said plug being provided with a key-way, and said lock operating member being provided with a key-receiving driving recess located adjacent to the key-way of the plug.

7. Lock mechanism comprising associated cylinder and plug members, and a lock operating member sleeved upon and rotatable around said cylinder, said lock operating member and said plug member being coupled to rotate together and both being provided with means adapted for driving engagement with a key.

8. Lock mechanism comprising associated cylinder and plug members, and a lock operating member sleeved upon and rotatable around said cylinder, said lock operating member and said plug member being coupled to rotate together, a key-way in said plug member, and a key-receiving driving recess in said lock operating member and located adjacent to the key-way of the plug.

9. Lock mechanism comprising relatively

rotatable cylinder and plug members, tumbler mechanism therefor, a lock operating member sleeved upon and rotatable around said cylinder, said lock operating member being coupled to rotate with said plug member, and said plug member and said lock operating member both being provided with means adapted for driving engagement with a key.

5 10. Lock mechanism comprising relatively rotatable cylinder and plug members provided with a cooperating tumbler mechanism, said plug being provided with a multiple-way slot to receive a multiple ward key adapted to actuate said tumbler mechanism, a lock operating member associated with said cylinder and coupled to rotate with said plug member, said lock operating member being provided with a key receiving driving recess located adjacent to the key-receiving slot of

15 20. said plug.

In testimony whereof I hereby affix my signature.

ANDREW MAIN.
